UNITED STATES PATENT OFFICE.

HAROLD H. WILL, OF SYRACUSE, NEW YORK, ASSIGNOR TO THE WILL & BAUMER CO., OF SYRACUSE, NEW YORK, A CORPORATION OF NEW YORK.

DESIGN FOR A CANDLE.

52,776.

Specification for Design.

Patented Dec. 17, 1918.

Application filed August 29, 1916. Serial No. 117,548. Term of patent 14 years.

To all whom it may concern:

Be it known that I, HAROLD H. WILL, a citizen of the United States, residing at Syracuse, in the county of Onondaga and State of New York, have invented a new, original, and ornamental Design for a Candle, of which the following is a specification, reference being had to the accompanying drawing, forming a part hereof.

In the drawings, Figures 1 and 2 are respectively a plan and a side elevation of the candle embodying my design.

This design for candle comprises a body or a shaft rising from a butt or base, a plu-

rality of ribs *a* extending lengthwise of the body or shaft and formed of substantially uniform height or distances out from the shaft, and additional ribs *b* extending lengthwise of the body between the ribs *a* and formed of less height than the ribs *a*.

I claim:

The ornamental design for a candle, substantially as shown and described.

In testimony whereof, I have hereunto signed my name, at Syracuse, in the county of Onondaga, and State of New York, this 9th day of June, 1916.

HAROLD H. WILL.
